A water circulating pump supported within the bathtub, the pump having a discharge outlet which can be rotated to control the direction of discharge. The control of the direction is achieved by a manually rotatable sleeve located above the pump and surrounding a portion of the exterior casing for the unit. The sleeve is coupled with the pump housing by a hollow tube which encases a rotatable control shaft for a pump discharge flow control valve and also provides a conduit for induction of air into the discharge from the pump. A manual adjustment handle for the valve control shaft also provides a means of controlling the air flow.

CONTROL ASSEMBLY FOR BATHTUB HYDROTHERAPY UNIT

BACKGROUND AND SUMMARY OF THE INVENTION

This invention relates to a portable water circulating unit that can be used in a standard bathtub for therapeutic effects.

In order to be easily installed and operated in conventional bathtubs, a portable water circulating unit, sometimes called a whirlpool unit, should be light in weight, easily maneuverable, safe in operation and easily adjustable, both as to the flow rate and the direction of discharge. The unit according to my invention meets all of these requirements and is particularly characterized by a simple and safe control assembly relating to the control of the rate of discharge, the direction of the discharge into the tub and the induction of air when desired, into the discharged stream from the pump.

One of the principal objects of my invention is to provide a convenient and safe control assembly by which the direction of discharge of the circulating pump, the flow rate and induction of air can be varied at will without requiring the placing of the hand in the vicinity of the pump but instead, by placing it at a convenient location well above the pump and close to the surface of the water.

Another important object of the invention is to reduce as fast as possible the number of components required to provide structural support and operational effectiveness for the directional, flow rate and air induction controls.

Other and further objects of the invention together with the features of novelty appurtenant thereto will appear in course of the following description.

DETAILED DESCRIPTION

In the accompanying drawings which form a part of the specification and are to be read in conjunction therewith and in which like reference numerals indicate like parts in the various views:

FIG. 1 is a perspective view showing a preferred unit embodying the invention mounted in operating position on a conventional bathtub;

FIG. 2 is a fragmentary side elevational view, partly in section, of the inner section of the housing for the unit, showing the pump and the control assembly;

FIG. 3 is a fragmentary sectional view on an enlarged scale taken along line 3-3 of FIG. 2 in the direction of the arrows;

FIG. 4 is a sectional view on an enlarged scale taken along line 4-4 of FIG. 2 in the direction of the arrows;

FIG. 5 is a fragmentary sectional view on a still further enlarged scale showing the rotatable support components for the pump housing.

The preferred embodiment of the invention comprises a hollow casing, 10, in the shape of an inverted U which houses the operating elements of the unit. This casing 10, which may be made of a light weight plastic, consists of an upper portion 11 and lower portion 12 which are secured together by means of screws 13 (FIG. 2). The upper portion 11 contains a handle 14 for lifting and maneuvering the unit as a whole. The lower portion has a section 12a outside the tub and a section 12b inside the tub. The pump is indicated at 15, being at the lower end of housing section 12b. An elec-

tric motor (not shown) is located in section 12a and is used to transmit power to the pump in a manner similar to that described in U.S. Pat. No. 2,782,425.

The pump power is supplied through a drive shaft 16 which drives the rotary impeller 17 which is located within the pump housing 18. The impeller 17 draws water in through the perforations of a perforated plate 18a which is located on the underside of pump housing 18. Water is discharged through the outlet 19, which is formed integral with the pump housing 18.

The rotatable mounting of the pump housing 18 in relation to the casing section 12b is shown in FIGS. 3 and 5. The drive shaft 16 for the impeller is substantially centered in section 12b of the casing, and the lower end of the drive shaft is secured to the impeller 17. The lower end of the section 12b has an integral, inset depending collar member 21 having an inturned annular flange 21a. A flat ring 22 is located beneath the flange 21a and is secured thereto by means of screws 23, there being a small open space 24 between the flange 21a and the ring 22 (See FIG. 5).

The upper portion of the pump housing 18 is formed to provide an integral flange 25, the underside of which is provided with annular groove 26. The underlying ring member 22 contains a similar annular groove 27. These circular grooves 26 and 27 are positioned one above the other such that a ring 28 made of a low friction material can be placed in the respective grooves 26 and 27, thereby supporting the pump housing 17 upon the ring member 22 and permitting rotation of the pump housing 18 relative to the sections 12b of the casing. The axial position of pump housing 17 is stabilized by bearing contact between the inner edge of the flange 25 and the outer surface of collar 21, and between an upstanding annular boss 25a and the adjoining surface of casing section 12b.

The pump housing 18, can be rotated to channel the direction of flow from the discharge outlet 19 by means of rotating a sleeve 32 which is rotatably fitted onto the casing section 12b above the pump. The sleeve 32 circumscribes the casing section 12b and includes an integral boss 33 which is parallel with the sleeve axis through which there is a cylindrical passage 34. A portion of a tube 35 is anchored within the passage 34, the lower portion of the tube 33 extending into and being anchored within a similar cylindrical passage 36 formed an upwardly extending boss 37 integral with the pump housing 18 and discharge outlet 19. When the sleeve 32, the upper portion 38 of which is provided with parallel ridges to facilitate obtaining a firm grip, is rotated, the rotation is transmitted by the tube 33 to the pump housing 18 to rotate it in the same direction, thus to change the position of the discharge outlet 19. The tube 33 is anchored against rotation or vertical movement by a set screw 39 extending through the wall of the upwardly extending boss 37 of the pump housing by a set screw 40 extending through the wall of the boss 37 on the sleeve.

Contained within the tube 35 is a shaft 41 which is generally centered in the tube and free to rotate. The upper portion of the shaft 41 contains threads 43 which mesh with the threads 44 of an internally threaded member 45 that is secured to the top of the vertical tube 35. Secured to the top of the inner shaft 41 is a control handle 46. The handle rotatably circumscribes the tube 33. Thus when the control handle 46 is rotated, the meshing of the two sets of threads 43 and 44

causes the inner shaft 41 to move either up or down relative to the tube 35, depending on the direction of rotation of the control handle 46. The vertical distance that the inner shaft 41 can be moved is restricted by the number of threads 43 on the shaft so that when the threads 43 of the inner shaft 41 cease to mesh with the threads 33 of the internally threaded member 45, the inner shaft 41 is unable to move any further in that direction.

Contained within the discharge outlet 19 is an oval shaped, hinged valve 47 supported by hinge pin 48 that extends through the sides of the discharge outlet 19. When water is discharged from the outlet 19, the pressure of the water forces the front section of the valve to rise, thus opening the valve 47 and allowing the water to pass through it. The inner shaft 41 is located such that its lower extremity is capable of coming into contact with and depressing the front section of the valve 47. This downward contact pressure of the inner shaft 41 on the valve 47 counteracts the water pressure and thus the valve 47 can be fully closed, partially closed, or fully opened, depending on the position of the inner shaft 41. In this manner the inner shaft 41 and valve 47 can be used to control the rate of discharge of water into the tub.

A series of apertures 49 are arranged in a vertical row in one side of the control handle 46. There is also a co-operating air opening 50 in the tube 33. The apertures 49 in the control handle 46 can be aligned, partially aligned, or not aligned at all with the opening 50 in the tube 33, depending on the rotational position of the handle 46, for any vertically adjusted position of the control handle. The discharge of water through outlet 19 induces a negative pressure within the tube. When the apertures 49 in the handle are aligned with the opening 50, air enters the tube 33 through them and flows to the bottom of the tube, where it intermixes with the liquid flowing from the outlet 19. By alignment or partial alignment of the air holes the amount of air intermixed with the liquid can be regulated.

From the foregoing, it will be seen that this invention is one well adapted to attain all of the ends and objects hereinabove set forth together with other advantages

which are obvious and which are inherent to the structure.

It will be understood that certain features and sub-combinations are of utility and may be employed without reference to other features and subcombinations.

As many possible embodiments may be made of the invention without departing from the scope thereof, it is to be understood that all matter herein set forth or shown in the accompanying drawings is to be interpreted as illustrative and not in a limiting sense.

Having thus described my invention, I claim:

1. In an apparatus for circulating water in a tub, said apparatus including a centrifugal pump for immersion in the tub and a vertical casing extending thereabove for housing the pump drive shaft, the improvement comprising:

a centrifugal pump housing supported on the bottom end of said casing and rotatable relative thereto, said pump housing having an inlet and a lateral discharge outlet.

a valve member mounted interiorly of said outlet for controlling flow therethrough, a sleeve circumscribing said casing above the pump housing and rotatable in relation to the casing, and

rigid connecting means connecting the sleeve to the pump housing to effect angular adjustment of said outlet in response to rotation of the sleeve, said rigid means including means for controlling the operation of said valve.

2. The improvement of claim 1, said rigid means including, a hollow tube extending between said sleeve and housing, and

a shaft threadingly engaged within said tube and rotatable therein for vertical movement to operate said valve member.

3. The improvement as in claim 2, said tube communicating at its lower end with the interior of said outlet, said tube having

air flow control means at its upper end operable to control the ingress of air to the tube and to effect rotation of said shaft.
